UNITED STATES PATENT OFFICE.

WILLIAM HENRY HILLER, OF TORONTO, ONTARIO, CANADA.

REIN-HOLDER.

SPECIFICATION forming part of Letters Patent No. 339,887, dated April 13, 1886.

Application filed October 26, 1885. Serial No. 181,034. (No model.) Patented in Canada September 28, 1885, No. 22,543.

To all whom it may concern:

Be it known that I, WILLIAM HENRY HILLER, a subject of the Queen of Great Britain, residing at the city of Toronto, in the county of 5 York and Province of Ontario, Canada, have invented certain new and useful Improvements in Line or Rein Holders, (for which I have received Letters Patent in the Dominion of Canada, No. 22,543, dated September 28, 1885;) 10 and I do hereby declare that the following is a full, clear, and exact description of the same, reference being had to the accompanying drawings.

Figure 1 is an end view of a bolt with nut 15 or thumb-screw and loose fastening, which forms part of my invention. Fig. 2 is a front view of one of two clamps or holders, which forms part of my invention. Fig. 3 is a plan of the same.

20 The line or rein holder, as shown in Fig. 3, consists of a frame, D, being substantially constructed of brass or other material strong enough to stand the working of the line-holder, and having the upwardly-projecting arms D'. The two clamps A A are placed opposite to each other a distance apart, as shown in Fig. 3, in the frame D. The pins B B, which pass through the two arms of the 25 said clamps A A at the points H H, respectively, are fastened into the frame D above and below, the said clamps A A oscillating forward and backward on the said pins B B in a free and easy manner. Then the lower part of the front side of each of the clamps A A is 30 filed or cut away equally alike, so they work to the front a trifle past the center and rest against the projection S in the said frame D, thereby leaving the two clamps or holders farther apart in front than behind.

35 Again; the two knobs or flanges G G, also shown in Fig. 2, formed by the said filing or cutting away on the said clamps A A, respectively, catch against the ends of the projection S, and prevent the two clamps A A 40 working too far back in the frame D. Then two coils of brass or other wire are wound around each of the pins B B, between the arms H H of the respective clamps A A. One end of said wire catches on the back part of the 45 clamps aforesaid, respectively, below the upper arm H, and the other end against the back part of the frame D above the lower arm H,

thereby forming two very strong spiral or coil springs, C C, which operate directly and together on the clamps or holders A A. The 55 said two clamps A A, respectively, as shown in Fig. 3, are bent over or rounded on the top and down over outside of the frame D, to enable the driver to throw his reins into the holder at the point T without impediment; 60 and the points of the said clamps A A are driven or bent as close to the frame D as possible, to prevent the reins, robes, clothing, or anything of that nature being caught in any part of the said frame or line-holder. The line-holder being securely fastened to the center of the dash-board rod, with the front or flaring side of the clamps outward, the driver drops or draws the reins into the space T between the said clamps A A, and, through the power 65 given to the said clamps by pressure outward against the projection S of the frame D, caused by the coil or spiral springs C C, and the clamps being situated past the center, making them wider apart in front than behind, together 70 with the two knobs G G, acting in unison with the springs aforesaid, causes the two clamps A A to work together, thereby creating a line-holder capable of holding properly a thin rein as well as a thick one. To release 75 the reins from the holder, you have only to raise them up.

The description of the second part of my invention is the mode of fastening the line-holder to the vehicle, which is as follows: The lower 80 part of the frame D sets out far enough to allow it to set on the center of the dash-rod and pass down over the front of the dash-board sufficient to form the outside of the fastening. Over the rod of the dash-board the loose fastener F is connected with the said lower part 85 of the frame D by the bolt E, (the end view being in Fig. 1,) passing over the dash-board and through the frame D, and is held there by a nut or thumb-screw, K, as shown in Fig. 90 1, while the loose fastener F is driven and bent around the dash-board rod securely, and forms the inside of the fastener or fastening. By tightening up the said nut or thumb-screw 95 K you hold the line-holder in position to do 100 its work, and have a complete line-holder and fastener.

What I claim as my invention, and desire to secure by Letters Patent, is—

In a rein-holder, the combination, with the frame D, having the projection S and upwardly-extending arms D' D', of the clamps A A, bent over at their upper portions and 5 having upper and lower arms, H H, the lower arms being provided with lugs G G, for bearing against the projection S, the pins B B, held in frame D and arms D' D', and the coiled

springs C C encircling said pins, their ends bearing, respectively, against the arms D' D' 10 and upper arms H H of the clamps A A, substantially as and for the purpose described.

WILLIAM HENRY HILLER.
